UNITED STATES PATENT OFFICE.

WALTER C. REED, OF DALTON, MASSACHUSETTS, ASSIGNOR TO PHILIP W. GOEWY, OF PITTSFIELD, MASSACHUSETTS.

SWELL-BOX FOR PIPE-ORGANS.

1,353,667.

Specification of Letters Patent. Patented Sept. 21, 1920.

Application filed November 23, 1916. Serial No. 132,991.

To all whom it may concern:

Be it known that I, WALTER C. REED, a citizen of the United States, residing at Dalton, in the county of Berkshire and State 5 of Massachusetts, have invented certain new and useful Improvements in Swell-Boxes for Pipe-Organs, of which the following is a specification.

In constructing swell boxes for pipe organs it has been the practice heretofore to connect the several shutters in such manner that they move simultaneously and to vary the swell effect by opening or closing the collective shutters to a greater or less extent. The present invention provides a swell box construction which is radically different from that above referred to in that the several shutters extend horizontally and are movable independently of one another, instead of being linked together, and each shutter is provided with its own operating mechanism, so that any shutter can be opened or closed without regard to the position of any other shutter and an increasing swell effect can be produced by opening the shutters successively. In this way it is possible not only to obtain fine gradations of swell effect by comparatively simple means but also to operate the several shutters by individual motors which are small and practically noiseless, thus avoiding the use of a motor which when powerful enough to operate all the shutters simultaneously is likely to be noisy and to take up considerable space. Other features of my invention relate to the shutter-operating mechanism, and provide for the control of the shutters either automatically or by the organist, or in both ways.

40 In the accompanying drawing:

Figure 1 shows in elevation the front of a swell box having its shutters constructed and arranged for operation in accordance with my invention;

45 Fig. 2 is a section on the line $\alpha-\alpha$ in Fig. 1;

Fig. 3 is a section on the line $\gamma-\gamma$ in Fig. 1; and

50 Fig. 4 is a partly diagrammatic view illustrating an arrangement for operating the shutters.

Referring first to Figs. 1, 2 and 3 of the drawing, 2 indicates a frame in which are pivotally mounted a number of shutters 3,

shown as extending horizontally one above 55 the other with their supporting pivots 4 located about midway between their upper and lower edges. The frame 2 and the shutters which it carries may be assumed to constitute the front of a swell box, of which 60 the remaining parts and the pipes which it contains are not illustrated as they may be constructed and arranged in the usual or any suitable way. The individual shutters 3 may also be constructed in the usual way, 65 with beveled edges arranged to permit all the shutters to open in the same direction and faced with strips 5, of felt or the like, in order to prevent noise when they close.

The shutters 3 are provided with means 70 for opening and closing them independently of one another, and preferably, for reasons which will hereinafter appear, the shutters are closed by means of a corresponding number of independently-controlled pneumatic 75 motors, one for each shutter, and each shutter is subjected to a force constantly tending to open it, so that it will open automatically unless restrained from doing so and will stay open except when purposely closed 80 by the corresponding motor. In the construction illustrated the opening movement of each shutter is effected by a weight 6 secured to the shutter above its supporting pivots and on the outer side of the shutter, 85 the shutters being arranged to open outward at their upper edges, and each shutter-closing motor consists of a fixed block 7 secured to the frame 2 and carrying a bellows 8, the movable outer wall of which is connected by 90 a link 9 to the corresponding shutter 3 near the lower edge of the latter, so that when air under pressure is admitted to the interior of the bellows the resulting expansion of the latter closes the shutter and holds it 95 closed until the air within the bellows is permitted to escape.

Air is supplied to the interior of the bellows 8 and permitted to escape therefrom through passages formed in the block 7 and 100 comprising ducts 10 and 11 connected by an intermediate chamber 12, from which an exhaust perforation 13 leads to the outer air, the outer end of the duct 10 being connected to any suitable reservoir containing 105 air under pressure, such as the organ bellows (not shown). The chamber 12 contains two valves 14 and 15 which are car-

ried by a stem 16 and are a little smaller in diameter than the chamber 12, so that air can pass around them when open. These valves 14 and 15 control the duct 10 and the exhaust perforation 13 respectively, and are so located with respect to each other on the stem 16 that when either valve is open the other valve is closed. Both positions of the combined valves are illustrated in Fig. 1, in which the valves corresponding to the bottom shutter 3 are shown in their lowermost position, with the duct 10 closed and the perforation 13 open. When the valves are moved into this position the air pressure within the bellows 8 is relieved through the perforation 13 and the corresponding shutter is opened by the weight 6 attached thereto. When the combined valves are raised to their uppermost position, shown in connection with the shutter next above, the perforation 13 is closed and air under pressure enters the bellows 8 through the ducts 10 and 11, thereby closing the shutter and holding it closed until the valves are moved downward.

From the foregoing description it will be evident that by providing for the independent operation of the several valve stems 16, any shutter may be caused to open or close independently of any other shutter and regardless of the position of the other shutters. It is this capacity for individual movement which makes it desirable to arrange the shutters horizontally, since in such case the swell effect produced by the opening of any shutter is distributed uniformly across the full width of the swell box and affects to an equal extent the loudness of all the pipes in the box, whereas if the shutters were arranged vertically and a single shutter only were opened the pipes next to that shutter would sound louder than the others.

For operating the valves above described I prefer to employ a series of electro-magnets 17, each having its armature 18 connected to the upper end of one of the valve stems 16 and so arranged that when the magnet is energized the corresponding valves 14 and 15 are moved downward into their lowermost position, thereby causing the corresponding shutter to be opened. Any suitable type of magnet may be employed, so far as the present invention is concerned, the magnet illustrated being constructed substantially as set forth in U. S. Letters Patent No. 1,165,904, granted December 28, 1915, to the Telelectric Company, on an application filed by myself. In a magnet of this type the armature is pivotally mounted 60 end is provided with a spring constantly tending to swing it outward and upward, with reference to the position shown in Fig. 1, so that when either of the magnets 17 is de-energized the spring just referred to causes 65 its armature to lift the valve stem 16 to

which it is connected and thus brings about the closing of the corresponding shutter in the manner already described.

The number and size of the individual shutters 3 may evidently be varied according to the space available for their reception and the number of gradations in the swell effect which it is desired to obtain, and the several shutters may be caused to open in any desired sequence by energizing the corresponding magnets 17 in the same sequence. I prefer, however, to control the energizing circuits of said magnets in such manner that an increasing swell effect is produced by opening the shutters in order, commencing with the bottom shutter, for the reason that the first increase in loudness should be relatively slight and I have found that the lowermost shutter has the least appreciable effect on the sound. An arrangement under the control of the organist for causing the shutters to open successively in the manner above referred to is illustrated diagrammatically in Fig. 4, in which the motors 8 and the magnets 17 are arranged in the same order as in Fig. 1, the shutters themselves being omitted.

In Fig. 4, 19 indicates a pivotally-mounted lever adapted to be operated by the foot of the organist and carrying a metal blade 20, which is connected by circuit wires 21 and 22 to one of the poles 23 of a suitable source of electric current, such as a generator 24. The blade 20 co-operates with a series of fixed metallic brushes 25, one for each magnet 17, each brush being connected by circuit wires 26 and 27 to the corresponding magnet, from which the current passes through a circuit wire 28 to a common return wire 29 connected to the other pole 30 of the generator 24. The brushes 25 are so arranged that when the lever 19 is in one of its extreme positions, shown in dotted lines in Fig. 4, the blade 20 is out of contact with all of the brushes, so that the circuits through all the magnets 17 are open and all the shutters 3 are therefore closed, but when the upper end of the lever 19 is depressed the blade 20 makes contact first with that one of the brushes 25 which corresponds to the lowermost magnet 17, thus causing the lowermost shutter to be opened, the remaining shutters being caused to open successively by a continued downward movement of said blade 20 until the latter is in contact with all the brushes, as shown in full lines in Fig. 4, and all the shutters 3 are open. Hence the number of shutters which are open at any given time will depend upon the position of the lever 19, the order in which they are closed being the opposite of that in which they are opened. The rate of increase of the swell effect resulting from the opening of more than one shutter will evidently depend upon the rate of movement 130

of the lever 19, which will be governed by the judgment of the organist, while the swell effect resulting from the opening of any one shutter may be caused to increase at any 5 desired rate by suitably proportioning the weights 6 to the resistance offered by the shutters to the shutter-opening tendency of these weights.

Fig. 4 also shows an arrangement for controlling the magnets 17 automatically, comprising a metal blade 31 connected by a wire 32 to the circuit wire 22 and a set of fixed brushes 33 supported on a base board 34 and severally connected to the circuit wires 27. 10 The brushes 33 are arranged in relation to one another and to the blade 31 in the same way that the brushes 25 and blade 20 are arranged, so that when the blade 31 moves toward said brushes 33 it makes contact with 15 the latter successively, commencing with the brush which is connected to the lowermost magnet 17. For moving the blade 31 into and out of contact with the brushes 33 I employ a pneumatic motor, shown as consisting 20 of two bellows 35 and 36 carried by fixed blocks 37 and 38 and having their movable walls connected at their upper ends by a link 39 and so arranged that when either bellows expands the other contracts. The 25 blade 31 is carried by the movable wall of the bellows 35 and is out of contact with any of the brushes 33 when the bellows 36 is fully expanded but is in contact with all of said brushes when the bellows 35 is fully expanded. The bellows 35 is caused to expand by admitting air under pressure to its 30 interior through a duct 40 formed in the base board 34 and block 37 and communicating with a passage 41 which leads at one end to the outer air and at its other end to a chamber 42, to which the air under pressure is admitted through a pipe 43 connected to the organ bellows or other source of supply. The passage 41 is controlled by two 35 valves 44 and 45 carried by a stem 46 and so arranged that when these valves are moved into their lowermost position said passage is closed at its upper or inner end by the valve 44 and is opened at its outer end by the valve 45, thus permitting the air within the bellows 35 to escape, while when 40 said valves are in their uppermost position the passage 41 is closed at its lower end and open at its upper end, so that communication between the chamber 42 and the duct 40 is established and the air pressure is admitted to the bellows. In like manner air 45 under pressure is admitted to the interior of the bellows 36 and permitted to escape therefrom through a duct 47, a passage 48 controlled by valves 49 and 50 carried by a valve stem 51, and a chamber 52 connected to the pipe 43. The valve stems 46 and 51 are raised and lowered by electro-magnets

53 and 54, which are shown as having the 65 same construction as the magnets 17 but inverted in position, so that their armatures 55 and 56, which are connected to the upper ends of the stems 46 and 51 respectively, raise said stems when the magnets are energized and lower them when the magnets are deenergized.

The valves 44 and 45 are shown in their lowered position, the magnet 53 being deenergized, and the valves 49 and 50 are shown 75 in their elevated position, where they are held by the energized magnet 54, so that the bellows 36 is expanded and the blade 31 is held out of contact with all the brushes 33. All the shutters 3 will therefore be closed, 80 assuming that the foot lever 19 is not employed or is in its inoperative position. If now the magnet 53 is energized and the magnet 54 is deenergized the blade 31 will evidently be moved toward the brushes 33 by 85 the expansion of the bellows 35, thereby causing the shutters 3 to open in order as fast as said blade reaches the corresponding brushes, but this movement of the blade may be arrested as soon as any desired number 90 of the shutters have been opened by deenergizing the magnet 53 without energizing the magnet 54, since neither bellows will then be subjected to any force tending to expand it and the blade 31 will therefore 95 remain at rest until one magnet or the other is energized. The same result will be obtained if both magnets are energized with the blade 31 in a given position, since in such case a balanced air pressure will be established within both bellows and the blade 100 will remain motionless until one magnet or the other is deenergized. In like manner the blade 31 may be caused to move out of contact with a part or all of the brushes 33, 105 so that any number of the shutters 3 may be caused to open or close at any time by suitably controlling the energizing circuits of the magnets 53 and 54. The rate of movement of the blade 31 may be conveniently 110 regulated by means of screws 57 and 58 entering the ducts 40 and 47 respectively, by the adjustment of which screws the flow of air through said ducts may be obstructed sufficiently to retard the movement of the 115 corresponding bellows to any desired extent. The automatic arrangement just described is particularly adapted and intended for use in connection with an automatic playing apparatus controlled by a perforated music 120 sheet, since it enables the shutters to be completely controlled by providing the music sheet with two lines of special slots. Such a playing apparatus is diagrammatically represented in part by the contact bar 125 59 connected by a circuit wire 60 to the pole 23 and coöperating with two contact fingers 61 and 62, of which the finger 61 is connect-

ed by a circuit wire 63 to the magnet 53 and the finger 62 is connected by a circuit wire 64 to the magnet 54, the circuits through the respective magnets being completed by means of wires 65 and 66 leading therefrom to the common return wire 29. Assuming that the fingers 61 and 62 are controlled by the music sheet (not shown) in such manner that whenever a slot in the sheet passes beneath either finger the latter makes contact with the bar 59 during an interval proportionate to the length of the slot, it will be evident that any desired number of closed shutters 3 may be opened by causing a slot 15 of appropriate length to pass beneath the finger 61 and that any desired number of open shutters may be closed by causing a slot of appropriate length to pass beneath the finger 62, these slots being proportioned 20 in accordance with the rate of movement of the music sheet and of the blade 31.

The shutter-controlling mechanism shown in Fig. 4 has the advantage that both the foot-operated lever and the automatic mechanism may be associated in the same 25 apparatus and used independently of each other, although either arrangement may obviously be employed to the exclusion of the other if desired. When the automatic mechanism is operating the foot lever will ordinarily be thrown out of action by moving it into its dotted-line position, but the organist can at any time increase the swell effect by means of the foot lever, since the 30 magnets 17 can be energized through either of the two sets of brushes 25 and 33. When it is desired to control the shutters by means of the foot lever only, the blade 31 is moved out of contact with all the brushes 33, which 35 may be done by closing a normally-open branch circuit through the magnet 54, in parallel with the circuit through the finger 62. Such a branch circuit is represented by the circuit wire 67 connecting the wire 64 40 with the pole 23 and including a normally-open switch 68, which is shown as a manual switch, although in practice this branch circuit will ordinarily be closed automatically 45 by means not necessary to be described.

50 It will be observed that whenever the air is shut off from the organ all the shutters 3 will open automatically, whether the magnets 17 or any of them are energized or not, and this is an important advantage of the 55 shutter-operating mechanism illustrated in Figs. 1, 2 and 3 because it insures a free circulation of air through the swell box when the organ is not in use.

I claim:

1. A swell box for pipe organs comprising 60 a series of shutters each provided with means including an electro-magnet for operating it independently of any other shutter, in combination with a set of brushes electrically connected respectively to the several 65 magnets, a blade movable into and out of contact with said brushes successively, magnet-energizing circuits including said blade and brushes, blade-operating means comprising two pneumatic motors acting in opposition to each other, and means for independently controlling said motors. 70

2. A swell box for pipe organs comprising 75 a series of shutters each provided with means including an electro-magnet for operating it independently of any other shutter, in combination with a set of brushes electrically connected respectively to the several 80 magnets, a blade movable into and out of contact with said brushes successively, magnet-energizing circuits including said blade and brushes, blade-operating means comprising two pneumatic motors acting in opposition to each other and each 85 provided with an electro-magnet for controlling its operation, and means for energizing and deenergizing said magnets independently of each other. 90

3. A swell box for pipe organs comprising 90 a series of shutters each provided with means including an electro-magnet for operating it independently of any other shutter, in combination with magnet-energizing circuits each corresponding to one of the magnets and including two branches, means 95 adapted to be operated by the organist for controlling one set of branch circuits, and means for automatically controlling the other set of branch circuits. 100

4. A swell box for pipe organs comprising 105 a series of shutters extending horizontally one above another and each provided with means including an electro-magnet for operating it independently of any other shutter, in combination with magnet-energizing circuits each corresponding to one of the magnets and including two branches, means adapted to be operated by the organist for controlling one set of branch circuits 110 in a predetermined order, and means for automatically controlling the other set of branch circuits in the same order. 115

Signed at Pittsfield, Mass., this 17th day of November, 1916.

WALTER C. REED.
